UNITED STATES PATENT OFFICE.

HOWARD M. DUDLEY, OF PHILADELPHIA, PENNSYLVANIA.

DYEING-MACHINE.

1,259,840.

Specification of Letters Patent.

Patented Mar. 19, 1918.

Application filed March 31, 1917. Serial No. 158,803.

To all whom it may concern:

Be it known that I, HOWARD M. DUDLEY, a citizen of the United States, and a resident of Philadelphia, in the county of Philadelphia and State of Pennsylvania, have invented certain new and useful Improvements in Dyeing-Machines, of which the following is a specification.

My invention relates to dyeing machines 10 and refers particularly to those machines in which textile fibers are dyed under compression, the dye liquor being forced through the compressed mass.

The dyeing of fibers under these conditions presents many difficulties, as it is essential that all parts of the fiber mass be treated absolutely equally by the dye liquor, as otherwise uneven results will be obtained.

This equal treatment is dependent upon a 20 number of conditions; the fiber must be uniformly and properly compressed, the liquor must be at a uniform pressure throughout the fiber mass, the formation of channels or passages within the fiber mass must be avoided, the dye liquor must be of such dilution as to prevent precipitation upon the fiber, the temperature of the liquor must be properly retained and means must be employed for determining the condition of the 25 dyed fibers without interrupting the dyeing operation, opening the dyeing chamber or disturbing or sampling the fiber being dyed.

The device of my invention accomplishes all of the above results in a manner economical 35 in construction and cheap, simple, accurate and positive in operation, and possesses other advantages which will be evident upon a consideration of my specification, drawings and claims.

As a means for preserving uniform pressure throughout the fiber mass, preventing the formation of channels and causing an even and uniform distribution of the dye liquor, I inclose the compressed fiber between two foraminous plates, the plates being composed of parallel upwardly and downwardly extended pyramidal bars, the sides of which have longitudinal openings to allow of the passage of the liquor. In 45 order to obtain a uniformly distributed pressure against the outer face of one of the foraminous plates, I introduce an upwardly and downwardly extended conical member within the flow of liquid thus equalizing 50 any differences of pressure that may result

from the formation of the chamber or the source of liquid supply.

In order to judge of the condition of the process, I have a small dyeing device exactly similar and proportionate to the larger 60 device and so constructed that fiber inserted therein will receive exactly the same treatment as that in the larger device, the same proportionate amount of the same liquor passing through both under the same 65 pressure and temperature, so that in order to determine the condition of the dyeing, the operation in the large device need not be even interrupted, the large device need not be opened, and it will not be necessary to 70 disturb the fiber contained therein. In addition to the evident saving in time incident to this method of testing, there is the further great advantage that in the case of dyeing yarns, as in skeins, chains, or warps, 75 it is not necessary to break off a portion of the yarn, as is necessary when the determination must be made from the fiber in the large dyeing device.

I have found that these two devices may 80 be most advantageously connected to each other by means of a channel or passage within the walls of the larger dyeing device, as the conditions within the two devices are thus maintained in similarity in the most 85 economical, convenient and efficient manner.

In the drawings, illustrating modified forms of my device, similar parts are designated by similar numbers.

Figure 1 is a side view, partly broken 90 away.

Fig. 2 is a cross-section through the line 2—2 of Fig. 1.

Fig. 3 is a side view of the conical member and its supports with the surrounding 95 shell removed.

Fig. 4 is a top plan view of Fig. 3.

Fig. 5 is a broken enlarged view of a foraminous plate.

Fig. 6 is a top plan view of Fig. 7. 100

Fig. 7 is a side view of a modified form of means for supporting the conical member.

Fig. 8 is a broken enlarged view of a modification of the foraminous plate.

Fig. 9 is a cross-section through the line 9—9 of Fig. 8. 105

Fig. 10 is a cross-section through the line 10—10 of Fig. 8.

In the particular form of my device as shown in the drawings, a cylindrical shell 110

11 is attached to the conical shell 12 by means of the bolts 13, 13. An angular annular extension 14 of the shell 11, supports a fixed foraminous plate 15. The upper portion of the shell 11 carries a series of outwardly extended lugs 16, 16. An annular member 18, capable of abutment upon the foraminous plate 17, has an outwardly extended annular flange 19. The thumb-screw bolts 20, 20 extend through holes in the flange 19 and mesh with the threads in threaded holes in the lugs 16, 16. The plates 15 and 17 may thus be maintained at any desired distance from each other. A pipe 21 connects the upper portion of the chamber within the shell 11 to the top of a reserve tank 22. The bottom of the tank 22 is connected by the pipe 23, carrying the valve 24, with the intake pipe 25 of the pump 26. The exit pipe 27 of the pump 26 is attached to the lower part of the shell 12 by the bolts 28, 28. The pipe 25 is connected by the pipe 29, carrying the valve 30, with a dye dissolving tank, not shown. The pipe 29 is also connected with the pipe 32 carrying the valve 33, pipe 32 being connected to a water supply source. A perforate steam pipe 31 is within the lower portion of the chamber of shell 11 and beneath the foraminous plate 15. The pipe 27 is connected to a drain or receiving receptacle (not shown) by the pipe 34, carrying the valve 35.

The foraminous plates 15 and 17 are of the same construction, and consist of a series of parallel upwardly and downwardly extended pyramidal bars 36, 36, the inclined sides of which have a series of slits or openings 37, 37 through which the liquor may be passed.

To facilitate reference to the drawings, the chamber above the plate 17 will be referred to as the overflow chamber 38, the chamber between the foraminous plates 15 and 17 as the dyeing chamber 39, the chamber within the shell 12 as the equalizing chamber 40, and the chamber within the exit pipe 27 of the pump 26 as the pump chamber 41.

Within the equalizing chamber 40 is an upwardly and downwardly extended conical shaped member 42, so situated that the pressure of any liquid discharged into the chamber by means of the pump 26 will be distributed equally throughout and hence be impinged uniformly upon the entire bottom of the foraminous plate 15. Extending outwardly from the conical member 42 to the shell 12 is a series of vertical plates 43, 43, which serve to support the member 42 and to aid the distribution of the liquid within the equalizing chamber 40.

Within the shell 11 is a conduit or channel 47 connecting the interior of the device below the plate 17 with the small device 48.

This connection is made by the pipe 49 threaded in the top of the conduit 47, the pipe 49 being joined to the pipe 50 by the swivel joint 51. The pipe 50 is connected to the thermometer 52 by the pipe 53, the liquid after passing the thermometer passing through the pipe 54 into the top chamber 38. The small device 48 is exactly similar and proportionate to the large device in every particular, and the liquid entering in through the pipe 50 leaves it through the pipe 55 into the top chamber 38. The pipe 49 carries the valve 56. The device 48 can be revolved upon the joint 51 into the position indicated in dotted lines, in order to remove it from above the larger device when it is desired to remove or introduce the foraminous plate 17.

By means of this construction, the condition of the fiber in the large dyeing chamber 39 may be determined at any time without interrupting the operation, opening the large device or displacing the fiber therein, by closing the valve 56 and examining the fiber in the small device 48.

The operation of the device is as follows: The goods to be dyed are placed upon the plate 15 and the foraminous plate 17 inserted thereon. The annular member 18 is then introduced and pressed downwardly by means of the thumb-screw bolts 20, 20, until the goods are in a proper condition of compression. All of the valves are closed with the exception of valves 30 and 56. The pump 26 is started, and the dye liquor passes downwardly through the pipe 29 into the pump 26, and is forced upwardly through the entire device and the goods contained therein, the operation in the smaller device being the same as in the larger. When sufficient dye liquor has been introduced, valve 30 is closed and valve 24 is opened, and the operation of the pump thus causes a continuous circulation of the dye liquor through the device and the goods contained therein, the conical member 42 with its attachments causing a uniform pressure of liquid upon the plate 15, and the formation of the foraminous plate causing a uniform treatment of the goods in the dyeing chamber. The foraminous plate 17 maintains an equal pressure throughout the mass of goods, as its perforations are the same as those in the plate 15.

When the dyeing operation is completed the pump is stopped and all the valves are placed in a closed condition except valves 35 and 56, when all the liquor in the device will be drained off. Valve 35 is then closed, pipe 21 connected with a drain, valve 33 opened and the pump started, by this means fresh water is forced through the device and the goods thoroughly and uniformly washed.

In the modification shown in Figs. 6 and 7, the conical shaped member 42 is supported

to the shell 12 by the diamond shaped bars 44, 44.

In the modification shown in Figs. 8, 9 and 10, the foraminous plates comprise a series of upwardly and downwardly extended serrated pyramidal bars 45, 45 having longitudinal openings 46, 46.

I do not limit myself to the size, shape, number or arrangement of parts as shown 10 and described, all of which may be varied without going beyond the scope of my invention as described and claimed.

What is claimed, is:

1. In a dyeing machine, in combination, 15 a receptacle having imperforate sides, a foraminous plate composed of a series of pyramidal bars having openings for the passage of a liquid within the receptacle, a second foraminous plate within the receptacle, means for moving the two plates with respect to each other and maintaining them at any predetermined distance from each other, a fiber chamber between the sides of the receptacle and the plates and means for 20 forcing a liquid through the device.

2. In a dyeing machine, in combination, 25 a receptacle having imperforate sides, a foraminous plate composed of a series of pyramidal bars having openings for the passage of a liquid within the receptacle, a second foraminous plate within the receptacle, means for moving the two plates with respect to each other and maintaining them at any predetermined distance from each other, a fiber chamber between the sides of the receptacle and the plates, a liquid 30 chamber below the fiber chamber, a member having upwardly and downwardly converging extremities within the liquid chamber and means for circulating a liquid through the device.

3. In a dyeing machine, in combination, 35 a receptacle having imperforate sides, a foraminous plate composed of a series of pyramidal bars having openings within the sides of the pyramidal bars for the passage of a liquid within the receptacle, a second foraminous plate similar to the first mentioned plate within the receptacle, means 40 for moving the two plates with respect to each other and maintaining them at any predetermined distance from each other, a fiber chamber between the sides of the receptacle and the plates and means for forcing a liquid 45 through the device.

4. In a dyeing machine, in combination, 50 a receptacle having imperforate sides, a foraminous plate composed of a series of pyramidal bars having openings within the sides of the pyramidal bars for the passage 55 of a liquid within the receptacle, a second foraminous plate similar to the first mentioned plate within the receptacle, means for moving the two plates with respect to each other and maintaining them at any predetermined 60 distance from each other, a fiber chamber between the sides of the receptacle and the plates and means for forcing a liquid through the device.

5. In a dyeing machine, in combination, 65 a receptacle having imperforate sides, a foraminous plate composed of a series of pyramidal bars having openings within the sides of the pyramidal bars for the passage 70 of a liquid within the receptacle, a second foraminous plate similar to the first mentioned plate within the receptacle, means for moving the two plates with respect to each other and maintaining them at any predetermined distance from each other, a fiber chamber between the sides of the receptacle and the plates, a liquid chamber below the fiber chamber, a member having upwardly and downwardly converging extremities 75 within the liquid chamber, and means for forcing a liquid through the liquid chamber and the receptacle.

6. In a dyeing machine, in combination, 80 a receptacle having imperforate sides, a foraminous plate composed of a series of pyramidal bars having openings within the sides of the pyramidal bars for the passage 85 of a liquid within the receptacle, a second foraminous plate similar to the first mentioned plate within the receptacle, means for moving the two plates with respect to each other and maintaining them at any predetermined distance from each other, a fiber chamber between the sides of the receptacle and the plates, means for allowing the removal of a liquid from above the fiber chamber, means for returning the liquid to the source of circulation, a liquid chamber below the fiber chamber, a member having upwardly and downwardly converging extremities 90 within the liquid chamber and means for circulating a liquid through the device.

7. In a dyeing machine, two similar and proportionate devices, one being larger than the other, each comprising a receptacle having imperforate sides, a fixed foraminous plate extending across the receptacle and integral with the sides, a second foraminous plate extending across the receptacle and slidable therein, means for maintaining the two foraminous plates at any predetermined distance from each other, a second receptacle connecting the first receptacle with a means of liquid supply, an overflow pipe connected with the first receptacle above the second foraminous plate and connected with the liquid supply, means for heating the liquid in the larger device, a conduit within the shell of the larger device, connecting the chamber below the fixed foraminous plate with the chamber below the fixed foraminous plate of the smaller device, and means for forcing a liquid continuously through the two devices.

8. In a dyeing machine, two similar and proportionate devices, one being larger than the other, each comprising a receptacle having imperforate sides, a fixed foraminous plate extending across the receptacle and integral with the sides, a second foraminous plate extending across the receptacle and slidable therein, the foraminous plates being identical and composed of a series of pyramidal bars having openings for the passage of a liquid, means for maintaining the two foraminous plates at any predetermined distance from each other, a second receptacle connecting the first receptacle with a

means of liquid supply, an overflow pipe connected with the first receptacle above the second foraminous plate and connected with the liquid supply, means for heating the liquid in the larger device, a conduit within the shell of the larger device, connecting the chamber below the fixed foraminous plate with the chamber below the fixed foraminous plate of the smaller device, means 10 for interrupting the flow of liquid through the smaller device without interrupting it through the larger device, and means for forcing a liquid continuously through the two devices.

15 8. In a dyeing machine, two similar and proportionate devices, one being larger than the other, each comprising a receptacle having imperforate sides, a fixed foraminous plate extending across the receptacle and integral with the sides, a second foraminous plate extending across the receptacle and slidale therein, the foraminous plates being identical and composed of a series of pyramidal bars having openings for the passage of a liquid, means for maintaining the 20 two foraminous plates at any predetermined distance from each other, a second receptacle connecting the first receptacle with a means of liquid supply, means within the second receptacle for causing an even pressure and distribution of the liquid upon the lower face of the fixed foraminous plate, an overflow pipe connected with the first receptacle above the second foraminous plate and connected with the liquid supply, means for heating the liquid in the larger device, a conduit within the shell of the larger device, connecting the chamber below the fixed foraminous plate with the chamber below the fixed foraminous plate of the smaller device, means for interrupting the flow of liquid through the smaller device without 25 interrupting it through the larger device, and means for forcing a liquid continuously through the two devices.

30 35

device, and means for forcing a liquid continuously through the two devices.

9. In a dyeing machine, two similar and proportionate devices, one being larger than the other, each comprising a receptacle having imperforate sides, a fixed foraminous plate extending across the receptacle and integral with the sides, a second foraminous plate extending across the receptacle and slidale therein, the foraminous plates being identical and composed of a series of pyramidal bars having openings for the passage of a liquid, means for maintaining the 40 two foraminous plates at any predetermined distance from each other, a second receptacle connecting the first receptacle with a means of liquid supply, means within the second receptacle for causing an even pressure and distribution of the liquid upon the lower face of the fixed foraminous plate, an overflow pipe connected with the first receptacle above the second foraminous plate and connected with the liquid supply, means for heating the liquid in the larger device, a conduit within the shell of the larger device, connecting the chamber below the fixed foraminous plate with the chamber below the fixed foraminous plate of the smaller device, means for interrupting the flow of liquid through the smaller device without 45 interrupting it through the larger device, and means for forcing a liquid continuously through the two devices.

Signed at New York city, in the county of New York and State of New York, this 26th day of March, 1917.

HOWARD M. DUDLEY.
